NevadaApplication May 27, 1939, Serial No. 276,238
In Great Britain June 14, 1938

4 Claims. (Cl. 95—2)

It is already known from my prior patents that a photographic dye-image may be produced by local dye destruction in a layer containing dyes or dye-forming substances and being in immediate contact with an uncolored layer containing a photographic silver image. The present invention relates to improvements in this process and to materials useful therein:

It has been found that when the process is used to obtain dye-images in a multi-layer material, difficulties are encountered in connection with the exposure of the different layers and it is one of the objects of the invention to provide multi-layer materials for three-color photography which are especially adapted to the above mentioned process. Further objects of the invention will be apparent from the description:

If the process is used for the production of three color pictures, a taking material is used which comprises a front layer, sensitive to blue light, a yellow dyed filter layer arranged immediately behind the front layer, and further light-sensitive silver halide emulsion layers, one of which is sensitized to green and the other one of which is sensitized to red. The yellow dye in the filter layer is resistant to the ordinary photographic treating solutions but is capable of being locally destroyed under the control of the photographic silver image when treated after development by the treating solutions known for this process. The support or a colorless separating layer is arranged between the yellow colloid layer and the immediately following light-sensitive layer. When a material of this kind is used as a taking material the yellow colored part-image is produced in a layer which is situated during the exposure behind the blue-sensitive front layer of the material and which acts as a filter layer preventing the other light-sensitive layers from being affected by blue light rays. The other two light-sensitive layers may be treated in any suitable manner to produce the other two part-images. For example, the second image or the third part-image, or both may be produced from dye-forming substances and this may be done by the process of my prior Patent No. 2,071,688, dated February 23, 1937. The dye image corresponding to the silver image produced in the rear layers of the material may also be formed by dyes present in the light-sensitive layer itself and in this case the dye present in the rear layer should have a lower bleaching speed than the yellow dye used for the production of the yellow part-image. Furthermore, it is possible to produce not only

the yellow dye image under the control of the silver image present in the preceding layer, but to produce also the second dye image or all of the dye images from pre-dyed layers under the control of the silver deposit present in the immediately preceding silver halide layer. For this purpose a light-sensitive material is used in which pre-dyed colored layers, which are free from light sensitive silver salts, are combined with light-sensitive silver halide layers and arranged in such a manner that behind the blue-sensitive layer a yellow colored colloid layer, behind the red-sensitive layer a blue-green colored colloid layer, and behind the green-sensitive layer a magenta-dyed colloid layer is arranged, layers of plain gelatin separating each colored layer from the following light-sensitive layer.

In the drawing I have illustrated various exemplifications of my invention. Fig. 1 shows an arrangement of light sensitive layers and intimately associated dyed gelatine layers, in which the material can be exposed from the side of the blue sensitive layer, to all of the three primary colors of the spectrum. Fig. 2 shows a different arrangement, adapted for printing, in which the green sensitive layer and the blue sensitive layer can be exposed from one side, and the other blue sensitive layer can be exposed from the other side.

For instance, in Fig. 1 the front layer of the light-sensitive material consists of an ordinary blue-sensitive emulsion. This emulsion should be a fine grain emulsion and the layer should be thinner than the usual negative layers. Behind the layer a yellow-colored gelatin layer is arranged which contains an easily destroyable azo dye such as, for instance, Chrysophenine G (Schultz Farbstofftabellen, Leipzig, 1931, 7th ed., vol. 1, No. 726) in a concentration of 2 grams per sq. m. The following layer is a thin layer of plain gelatin and this is followed by a green-sensitive silver halide layer in front of a gelatin layer colored with about 1 gram per sq. m. of the magenta dye Anthosine BN (Fierz-David, Kuenstliche Organische Farbstoffe, Berlin 1926, Vol. III, page 663). Between the magenta layer and the following red-sensitive silver halide layer there is coated a layer of plain gelatin, and behind the red-sensitive layer there is arranged a blue-green colored gelatin layer containing 0.3 gram of the dye Brilliant Benzo fast green (obtainable by diazotising the azo dye from diazotised 2-naphthyl-amino-8-sulphonic acid and 1-amino-2-naphthol ethyl ether with sodium nitrite and hydrochloric acid, isolating the inter-

mediate product formed and adding it in admixture with water to a solution of 1-acetylaminio-8-naphthol-3,6-disulphonic acid which has been made alkaline by addition of sodium bicarbonate and to which pyridine has been added). The dye may be precipitated by calcium salts or salts of

present in one or more of the light-sensitive layers as shown, or in the colloid layers. The following table contains some of the various possibilities of combining the different layers, and Example 1 represents the arrangement shown in Fig. 2.

Color of the colored layers and sensitivity of the silver halide layers respectively

Sequence of the layers	Example 1	Example 2	Example 3	Example 4	Example 5	Example 6
Gelatin layer	Blue-green	Magenta	Yellow	Blue-green	Magenta	Yellow
Silver halide layer.	Blue-sensitive	Blue-sensitive	Green-sensitive	Blue-sensitive	Blue-sensitive	Green-sensitive
Do.....	Green-sensitive containing yellow filter dye.	Red-sensitive containing yellow filter dye.	Red-sensitive containing red filter dye.	Green-sensitive containing yellow filter dye.	Red-sensitive containing yellow filter dye.	Red-sensitive.
Gelatin layer	Yellow	Yellow	Magenta	Yellow	Blue-green	Blue-green
Do.....	Magenta	Blue-green	Blue-green	Magenta	Yellow	Magenta
Silver halide layer.	White or colored light.	White or colored light.	Green or red sensitive.	White or colored light.	Blue-sensitive	Green or red sensitive.

organic bases. The support may be situated in front of the blue-sensitive layer or behind the blue-green colored rear layer as shown, or the support may replace one of the colorless intermediate layers. The thickness of the colored gelatin layers may be adjusted to the different bleaching speeds of the dyes as described herein-after. After the exposure of the material in a camera with the blue-sensitive layer facing the lens, the silver images are produced by development and after fixing, the film is treated by one of the known dye-destroying solutions which, as described and claimed in my Patent 2,221,793 of Nov. 19, 1940, should contain an accelerating substance. After the removal of any remaining silver, a dye image in natural colors is obtained. This dye image may be printed on a printing material of the same general kind but the concentration of the dyes in the printing material should be lowered if the printing layers are applied to an opaque support for the production of color prints on paper or the like. The printing material is exposed behind the colored original and processed in substantially the same manner.

If the material is used as a printing material and has a transparent support as, for instance, in the production of kinematographic films a sound image may be printed into the light-sensitive layers for the production of a colored sound record or for the production of a black silver sound record.

In Fig. 2 is shown another multilayer material especially adapted to the production of three-color-prints according to the process of the invention. It comprises three light-sensitive layers which are sensitized and combined with three colored colloid layers in such a manner that each sensitive layer can be individually printed by colored printing light. The sequence of the superimposed light-sensitive layers and the colored layers is such that one outside layer is a colored layer whereas the opposite outside layer is a light-sensitive layer. Behind the colored outside layer there are arranged two light-sensitive layers, and behind the sensitive layer situated on the other outside there are arranged the remaining two colored layers. The support of the layers may be situated in such a manner as to separate the two neighbouring light-sensitive layers or the two neighbouring colored layers as shown. Alternatively, the support may be situated behind one of the outside layers. The dyes used for coloring the colloid layers are a yellow dye, a magenta dye and a blue-green dye, and the dyes referred to above may be used. Removable filter dyes may be

20 In the above examples, the two consecutive silver halide layers are to be exposed during printing from the direction of the colored outside layer, whereas the single light-sensitive layer situated on the other outside surface is exposed to printing light from this side. It is also possible to expose two layers from the side carrying the single emulsion layer and in this case it will be necessary to alter the sensitivity of the layers and possibly also to add filter dyes into the light-sensitive layers or to add an additional filter dye into the colored layers. Separate filter layers may be used between the sensitized layers. If all of the layers are to be printed upon from one side, the rear layer should be sensitive to infrared light.

25 The printing material is printed behind black and white positive part images or behind multicolor master positives of the well known kind. Each color selection positive is printed upon that light-sensitive layer which is adjacent to the layer colored complementary to the color sensation recorded in the partial positive. Thus, for example, the green color selection positive is used for printing on to the light-sensitive layer adjacent to the magenta dyed layer.

30 After the development of the silver images the whole material is treated with a dye destroying solution which may contain an accelerating substance in addition to the dye destroying agent.

35 The following solution, for example, may be used:

Potassium bromide..... 11.9 grams
Conc. sulphuric acid..... 27.9 ccs.
2,3-dimethyl quinoxaline..... 2.0 grams
55 Water ..... to 1 litre

In a multilayer material of the kind described it is sometimes difficult to select dyes having equal bleaching speeds, when treated with the same bleaching agent. This different behaviour results in shortcomings in the final multicolor picture.

60 In order to remedy this deficiency, the thickness of the individual layers of the multilayer material are adjusted to the bleaching speed of the dyes present therein.

The proportion of the thicknesses of the layers may be approximately arrived at in the following manner.

65 If, for instance, a yellow dye, a magenta dye and a bluegreen dye are to be used, and if to obtain a neutral grey, the dye concentrations of the three dyes have to be in the proportion of 2 grams:1 gram:0.3 gram per square metre respectively, then three dye solutions will be pre-

pared containing the said quantities of yellow, magenta and bluegreen dye in the same amount of gelatin. Equal volumes of the three dyed gelatin solutions are coated on equal surfaces of photographic layers containing a uniform silver deposit of equal density, the thickness of the dyed layers thus being practically equal.

Several samples of the three differently colored materials are now treated with the dye-destroying agent for say 10, 20, 30, 40, 50 and 60 minutes. After removal of the residual silver it may be found, for instance, that neutral grey will be obtained by superposing the sample of the yellow material treated for 30 minutes on the magenta sample that was treated for 20 minutes and on the bluegreen sample that was treated for 60 minutes. Then it follows that the bleaching times are in the ratio of 30:20:60, and the thicknesses of the layers containing the said dyes should be approximately in the proportion of $\frac{1}{3}:\frac{1}{2}:\frac{1}{6}$ or 2:3:1, and hence the layers should be prepared by adding 2 grams of the yellow dye to two volumes of gelatin solution, 1 gram of the magenta dye to 3 volumes of gelatin solution and 0.3 gram of the bluegreen dye to 1 volume of the gelatin solution. If the colored gelatin solutions thus prepared are applied to 1 sq. m. of the material, each one in direct contact with a sensitized silver halide layer, and each pair of dyed and silver halide layers possibly being separated from adjacent pairs of layers by a thin layer of gelatin, then the different bleaching speeds of the dyes will be compensated to a great extent by the difference in the thicknesses of the colored layers.

Differences may, however, result for example from the fact that the action of the treating solutions on the inner layers begins later than on the surface layer. The allowance for this difference may be arrived at by test and trial.

What is claimed is:

1. A light-sensitive multilayer material for the production of photographic dye images, comprising three selectively sensitive silver halide emulsion layers and three colored layers which are not light-sensitive, each of said colored layers being arranged in immediate contact with only one of the light-sensitive layers and being dyed with a reducible dye resistant to ordinary photographic treating solutions and capable of being locally destroyed under the influence of a metallic silver image, the layers being so arranged that one outside layer is formed by a light-sensitive layer behind which there are arranged two of the colored layers, whereas the other outside layer is formed by the third colored layer behind which there are arranged the other two light-sensitive layers.

2. A light-sensitive multilayer material for the production of photographic dye images, comprising three selectively sensitive silver halide emulsion layers and three colored layers which are not light-sensitive, each of said colored layers being arranged in immediate contact with only one of the light-sensitive layers and being dyed with a reducible dye resistant to ordinary photographic treating solutions and capable of being locally destroyed under the influence of a metallic silver image, the layers being so arranged that one outside layer is formed by a light-sensitive layer behind which there are arranged two of the colored layers, whereas the other outside layer is formed by the third colored layer behind which there are arranged the other two light-sensitive layers.

ing three selectively sensitive silver halide emulsion layers and three colored layers which are not light-sensitive, each of said colored layers being arranged in immediate contact with only one of the light-sensitive layers and being dyed with a reducible dye resistant to ordinary photographic treating solutions and capable of being locally destroyed under the influence of a metallic silver image, the layers being so arranged that one outside layer is formed by a layer sensitive to blue light behind which there are arranged two of the colored layers at least one of which is absorbent for blue light, whereas the other outside layer is formed by the third colored layer behind which there are arranged the other two light-sensitive layers.

3. A light-sensitive multilayer material for the production of photographic dye images, comprising three selectively sensitive silver halide emulsion layers and three colored layers which are not light-sensitive, each of said colored layers being arranged in immediate contact with only one of the light-sensitive layers and being dyed with a reducible dye resistant to ordinary photographic treating solutions and capable of being locally destroyed under the influence of a metallic silver image, the layers being so arranged that one outside layer is formed by a light-sensitive layer behind which there are arranged two of the colored layers, whereas the other outside layer is formed by the third colored layer behind which there are arranged the other two light-sensitive layers, said third colored layer being transmittant for blue light and one of the two light-sensitive layers arranged behind the third colored layer containing a yellow filter dyestuff.

4. A light-sensitive multilayer material for the production of photographic dye images, comprising three selectively sensitive silver halide emulsion layers and three colored layers which are not light-sensitive, each of said colored layers being arranged in immediate contact with only one of the light-sensitive layers and being dyed with a reducible dye resistant to ordinary photographic treating solutions and capable of being locally destroyed under the influence of a metallic silver image, the layers being so arranged that one outside layer is formed by a layer-sensitive to blue light behind which there are arranged two of the colored layers at least one of which is absorbent for blue light, whereas the other outside layer is formed by the third colored layer behind which there are arranged the other two light-sensitive layers, said third colored layer being transmittant for blue light and one of the two light-sensitive layers arranged behind the third colored layer containing a yellow filter dyestuff.
